UNITED STATES PATENT OFFICE.

OSCAR ERNEST HANS, OF TULSA, OKLAHOMA.

CAMPING OUTFIT.

Application filed February 21, 1922. Serial No. 533,379.

To all whom it may concern:

Be it known that I, OSCAR ERNEST HANS, a citizen of the United States, and a resident of Tulsa, in the county of Tulsa and State 5 of Oklahoma, have invented certain new and useful Improvements in Camping Outfits, of which the following is a specification.

My invention relates to camping outfits, and it consists in the combinations, constructions and arrangements herein described and claimed.

An object of my invention is to provide a camping outfit which is of simplified construction and is adapted to be attached to 15 an automobile of ordinary construction in such manner as not to retard the movement of the automobile in any way.

A further object of my invention is to provide a device of the character described 20 which can be detached from the vehicle to which applied at will and can be folded into small compass while in either detached or applied position, whereby the device is readily portable when detached.

25 A further object of my invention is to provide a device of the character described which will afford sleeping and housing accommodations for a plurality of persons when in set up position and which is adapted to completely house detachable parts thereof, as well as other articles such as baggage, when in folded position.

30 Other objects and advantages will be apparent from the following description, and the novel features of the invention will be particularly outlined in the appended claims.

35 My invention is illustrated in the accompanying drawings, forming a part of this application, in which:

Fig. 1 is a perspective view, showing an automobile equipped with my invention, the device being shown in folded position,

40 Fig. 2 is a view similar to Fig. 1, showing the device in set up position,

45 Figs. 3, 4 and 5 respectively are a side elevation, a plan view, and an end elevation of the device detached from the automobile and with the tent and the tent supporting elements thereof removed,

50 Fig. 6 is an end elevation of the device, illustrating to advantage the tent supporting elements comprised therein,

55 Fig. 7 is a perspective view of a coupling member included in the device,

Fig. 8 is a longitudinal section through the coupling member shown in Fig. 7,

Fig. 9 is a perspective view of a fragmentary portion of the device, portions thereof being broken away,

60 Fig. 10 is a perspective view showing fragmentary portions of tent supporting members comprised in the device and illustrating to advantage a coupling member included therein for connection with the coupling member illustrated in Fig. 7,

65 Fig. 11 is a section through a fragmentary portion of the device and through a support therefor, showing the means for detachably securing the device to the support, and

70 Fig. 12 is a side elevation of the structure shown in Fig. 11.

75 In carrying my invention into effect in the form now preferred by me, I provide a body or compartment comprising a flat bottom 1, parallel vertical sides 2 upstanding from the side edges of the bottom and being rigidly secured to the latter in any suitable known manner, an end member 3 hingedly attached at 4 to the bottom 1, and complementary top sections 5—5 hingedly attached, as at 6, at their remote edges to the sides 2—2 at the upper edges of the latter.

80 The parts described so far are made of a suitable material, such as wood, and in the embodiment of the invention illustrated, the bottom 1, the sides 2—2 and the top sections 5—5 are all substantially rectangular in configuration. The end 3 is so formed that the upper end thereof extends above the plane 85 of the upper edges of the sides 2—2 when it has been swung upwardly into vertical position as illustrated to advantage in Figs. 1 and 5 and the upper edge of the end member 3 is inclined downwardly in opposite directions from the median line thereof to its side edges.

85 The sides 2—2 are braced against lateral movement outwardly or apart by inclined braces 7 arranged at opposite sides thereof 100 with their bases secured to extensions 8 extending laterally of the bottom 1 and with their upper ends secured to the sides 2—2 adjacent to the upper edges of the latter. Associated with each brace 7 is a bar-like 105 support 9 which is pivotally attached at its lower end at 10 to the extension 8 and adjacent to the base of the brace 7. Each of the supports 9 is capable of limited movement about its pivotal connection at 10 from 110

a position in which disposed flatwise against the brace as indicated by the full lines in Fig. 5 to a position in which inclined upwardly and outwardly from the brace, as indicated by the dotted lines in Fig. 5. A keeper 11 is provided for each support 9 and is substantially of U-shape, as shown. A web portion of the keeper 11 is secured to the support 9 and the arms thereof straddle the brace 7 and extend beyond the inner side of the latter. A transverse pin 12 connecting the arms of the keeper adjacent to the ends of the latter will be moved into contact with the inner side of the brace 7 when the support 9 has been moved to the dotted line position of Fig. 5 and will hold the latter against further movement away from the brace.

Flat longitudinal members 13-13 are secured to the upper side of the top section 5-5 by right angular brackets 14, whereby the members 13-13 lie in planes extending substantially at right angles to the planes of the top sections 5-5. As shown in Fig. 5, the members 13-13 are arranged at such distances from the remote edges of the sections 5-5 that they will be close to the sides 2 when the sections have been swung outwardly into horizontal positions and thus tend to support the top sections 5-5 in outwardly swung horizontal positions, as illustrated in Figs. 5 and 6. The members 13-13 also cooperate with the sections 5-5 to retain upon the latter articles, such as pieces of luggage, placed thereon when the sections have been swung inwardly to rest upon the inclined upper sides of the end 3 and in contact with each other along their free sides, as illustrated in Figs. 1, 4 and 5.

The members 9 constitute the main support for the sections 5-5 when the latter have been moved outwardly into horizontal positions. The supports 9 are moved or swung outwardly into the position indicated by the dotted lines in Fig. 5 and by the full lines in Fig. 6 preliminarily to swinging the sections 5 outwardly into horizontal position. The sections 5-5 serve as beds or seats when in outwardly swung horizontal position. It is to be observed at this point that sufficient space is provided between the beds or seats to permit of convenient access thereto and of practically unrestricted movement between the beds or seats at opposite sides of the body.

In Figs. 11 and 12, I show the means now preferred by me for detachably securing the body to a supporting frame 15, which may be the frame of an automobile or other vehicle. In Figs. 1 and 2, the body is illustrated as being applied to an automobile 16 of the Ford roadster type of construction but obviously the application of the invention is not limited to a vehicle of this type. A hinge strap 17 is secured by bolts 18 to a

side of the body of the device and depends below the latter, being formed to provide a pair of aligned sleeve portions at its lower end, between which is disposed a sleeve portion 19 of a bolt 20. A pintle 21 is projected through the sleeve portions of the strap 17 and the bolt 20 to couple these parts together. A sleeve 22 having a flange 22' at its lower end is slidable upon the bolt 20 and is adapted to enter a notch 23 in the horizontal portion 24 of a Z-plate 25 which is secured to the frame 15 by bolts 26. When the bolt 20 has been swung toward the Z-plate 25 so that the sleeve 22 has been moved into the notch 23 and the flange 22' is located below the horizontal portion 24, a nut 27 engaging the bolt 20 is tightened until the flange 22' engages the under side of the horizontal portion 24.

In practice, I provide a plurality of the coupling connections just described at opposite sides of the frame of the automobile and at opposite sides of the body of the device, whereby the body of the device can be readily detachably and rigidly secured to the frame of the automobile in superimposed position thereon without the use of any special tool.

When the top sections 5-5 have been swung outwardly to horizontal position, as illustrated in Figs. 2 and 6, a structure for supporting a tent 28 may be placed thereon and detachably secured thereto. The tent supporting structure includes sets of tent poles such as indicated at 29 and 30 in Fig. 6. The tent poles 29 and 30 are pivotally connected to each other at the upper end of the tent pole 29 and at a short distance from the upper end of the tent pole 30. Connectors 31 are provided for the tent poles 29 and 30, each being pivotally attached at one end to the tent pole with which associated adjacent to the lower end of the latter and pivotally attached at its other end to a support 32 adjacent to the upper end of the latter.

The tent pole 30 has a coupling member 33 secured thereto above the point at which it is connected to the tent pole 29, as best seen in Figs. 6 and 10. The coupling member or element 33 comprises a flat base 34 carrying a hollow body 35 in which is disposed a spring-pressed latch 36, there being a transverse slot 37 through the upper wall of the hollow body, which slot is controlled by the spring pressed latch 36. The slot 37 through the upper side of the hollow body 35 communicates with slots 38-38 formed in the sides of the body 35, which slots extend toward the end of the hollow body remote from that at which the spring-pressed latch 36 is attached to the body by a pivot pin, as indicated at 39. A coupling member or element cooperating with the coupling element 33 comprises a pair of parallel lugs or ears 40-40 extending beyond the end of a

longitudinal member 41 to which they are attached and being connected adjacent to their outer ends by a transverse pin 42 adapted to be moved bodily through the slot 37 into engagement with the slot 38-38 of the hollow body 35, whereupon the spring-pressed latch 36 will move upwardly to prevent a return movement of the pin 42 through the slot 37.

10 It will be understood that I provide a set of the tent poles 29 and 30 and the parts appurtenant thereto at each end of the body of the device. The tent poles 29 and 30 of each set are correspondingly moved apart about 15 their pivotal connections with each other until the lower ends thereof rest upon the upper sides of the horizontally positioned sections 5-5. A coupling member including the parallel ears 40-40 and the transverse pins 42 is provided for each of the poles 29 and 30 and for each of the supports 32, being in each instance attached to the lower ends of the parts with which associated. Cooperating coupling members 33, 25 which have been hereinbefore described, are secured upon the sections 5-5 in position to cooperate with the coupling members carried by the tent poles 29 and 30 and the supports 32, whereby these parts may be secured 30 detachably to the sections 5 and supported in the position in which illustrated in Figs. 2 and 6. The supports 32 at opposite ends of the body of the device are adapted to support eave poles 43 and are provided with 35 coupling elements 33 at their upper ends cooperating with coupling members including the transverse pins 42 which are carried at the opposite ends of each eave pole. Similarly, the ridge pole 41 is provided at its opposite ends with 40 coupling elements including the transverse pins 42 for connection with the coupling elements 33, which, as hereinbefore stated, are attached to the tent pole 30.

45 From the foregoing description of the various parts of the device, the operation thereof may be readily understood. When the device has been applied to a vehicle, such as the automobile 16, in the manner described and it is desired to arrange the same in such manner as to provide sleeping quarters, the top sections 5-5 are swung outwardly into horizontal position and will be supported in the manner and by the 50 means described. The tent supporting structure which has been described in detail is assembled and mounted upon the sections 5-5, which are in position to serve as seats or beds. The tent 28 is then arranged on the tent supporting structure as 55 illustrated in Fig. 2 and by the broken lines in Fig. 6 so that the side edges of the tent depend below the plane of the sections 5-5. In the application of the device illustrated, 60 the top of the automobile 16 provides a par-

tial closure for one end of the tent and the fabric of which the tent is composed is arranged at the ends of the tent supporting structure to partially or entirely close the latter, as desired. The end 3 of the body 70 of the device may be swung upwardly into vertical position and secured to the fabric of the tent by suitable fastening means, none being shown. The tent is securely anchored to the body of the device by fastening means, such as the guy ropes or cables 44 which are attached at one end to flaps 45 secured by stitching to the fabric of which the tent is made and secured at their normally free ends to screw eyes 46 fast in 75 the sections 5 at intervals along the remote edges thereof.

80 Flaps 47 and 48 respectively may be attached as by rows of stitching along the upper edges thereof to the fabric of which the tent is made at the sides and front end of the tent, as illustrated in Fig. 9. The lower portions of the flaps 47 and 48 are adapted to be arranged in overlying relation to the horizontally positioned sections 5-5 and mattresses or bedding (not shown) may be placed upon the sections 5 after portions of the flaps have been arranged thereon, thereby practically closing the tent at 85 the sides and front end against the entrance 90 of cold air, snow, rain, or the like.

95 When it is desired to remove the device to another location or to proceed upon a journey, the tent is detached from the sections 5 and after being folded, is placed 100 within the body of the device. The tent supporting structure likewise is detached from the section 5 and the parts thereof are folded and arranged within the body of the device. The sections 5-5 are then 105 swung inwardly into the inclined positions in which illustrated in Figs. 1 and 5, the supports 9 are swung against the braces 7, and any luggage which cannot be placed 110 within the body of the device is placed upon the inclined top sections 5-5 to rest against the stops 13. Obviously, the movements of the vehicle to which the device is applied will not be retarded in the slightest 115 when the device is in folded position.

120 It will be manifest that my invention is susceptible of embodiment in forms other than that in which illustrated in the accompanying drawings, and I therefore consider as my own, all modifications and adaptations 125 of the form of the device disclosed herein which fairly fall within the scope of the appended claims.

I claim:-

1. In a camping outfit, a body having 130 spaced vertical sides, sections hingedly attached to said sides, said sections being swingable toward each other to provide a top for the body and away from each other substantially into horizontal positions, and

longitudinal stop members secured upon the normally upper sides of the said sections to extend longitudinally of the sections, said stop members being adapted to engage with the sides to brace the sections when the latter are in outwardly swung position and to cooperate with the sections to support luggage when the sections are in inwardly swung or closed position.

10 2. In a camping outfit, a body comprising a flat bottom having lateral extensions at opposite sides and adjacent to opposite ends thereof, vertical sides upstanding at opposite side edges of the bottom, complementary top sections hingedly attached to the vertical sides along the upper edges of the latter, and being swingable outwardly of the planes of the sides, an inclined brace member for each extension of the bottom, each brace member being secured at its lower end to one of the extensions adjacent to the outer end of the latter and being secured at its upper end to one of the sides at a point adjacent to the upper edge of the latter, a bar like support for each brace member, each bar like support being pivotally attached to one of the extensions between the outer end of said extension and the lower end of one of the brace members, and a keeper carried by each bar like support and engaging the ad-

55 jacent brace member to limit the swinging movement of said support outwardly from the brace, said bar-like supports being of a length to lie flatwise upon the associated brace members when in inwardly swung position and when in outwardly swung position to sustain the outwardly swung complementary top sections in horizontal position.

3. In a camping outfit, a body comprising a flat bottom having lateral extensions at 40 opposite sides and adjacent to opposite ends thereof, vertical sides upstanding from opposite side edges of the bottom, complementary top sections hingedly attached to the vertical sides along the upper edges of the latter and being swingable outwardly of the planes of the sides, an elongated supporting member pivotally attached at its lower end to one of said extensions, there being an elongated supporting member supported on 45 each extension, said elongated supporting members being swingable outwardly and inwardly from vertical planes to and from position to sustain the outwardly swung complementary top sections in horizontal 50 position, and means for limiting the swinging movement of the elongated supporting members relatively to said vertical planes.

OSCAR ERNEST HANS.
